Primary Examiner — Kathleen L Jones

(57) **CLAIM**

The ornamental design for a computer with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

1.1 : First front view

1.2 : Second front view in changed state

1.3 : Third front view in changed state

1.4 : Fourth front view in changed state

1.5 : Fifth front view in changed state

The broken lines showing a computer are for the purpose of illustrating environment and form no part of the claimed design; the dash-dotted broken lines define the bounds of the claimed design and form no part of the claimed design; the appearance of the transitional image sequentially transitions between the images shown in reproductions **1.1-1.5**; the process or period in which one image transitions to another image forms no part of the claimed design.

1 Claim, 5 Drawing Sheets
(5 of 5 Drawing Sheet(s) Filed in Color)
